(57) **CLAIM**

The ornamental design for a display screen with animated graphical user interface, as shown and described.

DESCRIPTION

FIG. 1 is a front view of a first image in a sequence for display screen with animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The appearance of the animated graphical user interface sequentially transitions between the images shown in FIGS. 1-6. The process or period in which an image transitions to another forms no part of the claimed design. The dashed broken lines within the peripheral dash-dot-dash lines illustrate portions of the animated graphical user interface, which form no part of the claimed design.

The peripheral dash-dot-dash broken lines illustrate a display screen and form no part of the claimed design.
